UNITED STATES PATENT OFFICE.

FRIEDERICK BAER, OF NEW YORK, N. Y.

AEROPLANE.

Application filed April 13, 1923. Serial No. 631,801.

To all whom it may concern:

Be it known that I, FRIEDERICK BAER, a citizen of Switzerland, residing at New York, in the county of New York and State of New York, have invented certain new and useful Improvements in Aeroplanes, of which the following is a specification.

This invention relates to certain new and useful improvements in aeroplanes, and it has for its objects among others to provide a special construction to take the place of all control wires in the event of disability, and to enable one to maintain perfect control of the aeroplane so that he may make a turn to the right or to the left, or take or prevent a nose-dive as may be desired, or to loop the loop, as well as to shorten the turn of the device or the loop.

It has for a further object to provide for lifting the weight of the motor so as to prevent the plane from striking the ground with great force, and also saving the device from tipping over on its nose as when forced to make a landing on a very bad field. On a smooth field the control blades may be so turned as to reduce the speed of the plane. The two blades are mounted for operation and control independent of each other, or in unison, and are so stable and strong as to be absolutely fool-proof in case of broken wires. Should both control wires break at the same time, by use of both hands one can change the controls from one position to another, and so on back and forth the same as if one was using a control stick. In actual flying the control will help to take the weight off of the motor if placed in neutral position and relieve the other control of heavy strain.

The present invention has for a further object to provide a light, yet strong and durable blade having its shaft so embodied therein as to give great rigidity combined with lightness, and also a bearing for the shaft, readily attachable to the engine bed and having roller bearings and an end thrust bearing. The shaft is formed with integral means for the attachment of a control member.

In my control I dispense with the employment of all wires and provide means of sufficient strength to withstand all strain. My control means may be employed for the same purpose even when the control wires or the flippers are not broken.

Other objects and advantages of the in-

vention will hereinafter appear and the novel features thereof will be particularly pointed out in the appended claims.

The invention, in its preferred form, is clearly illustrated in the accompanying drawings, which, with the numerals of reference marked thereon, form a part of this specification, and in which—

Figure 1 is a diagrammatic side elevation showing my invention applied to an aeroplane.

Figure 2 is a top plan.

Figure 3 is a perspective view of my control mechanism.

Figure 4 is a view partly in section and partly in elevation showing one of my improved blades or wings and the bearing for its shaft.

Figure 5 is a view looking down upon Figure 4, with the parts of the bearing in plan instead of in section.

Figure 6 is a longitudinal section through one of the blades or wings taken substantially centrally and flatwise thereof.

Figure 7 is an end view looking in the direction of the arrow 7 in Figure 4.

Like numerals of reference indicate like parts throughout the different views.

The aeroplane is indicated generally by the numeral 1, see Figures 1 and 2, and may be of any well-known or approved type, and hence will not be described in detail except in so far as pertains to my present invention, and for the same reason parts thereof not entering into or forming a part of, or necessary to, a proper understanding of my present invention have not been illustrated.

2 is the propeller, it being understood that the propeller, the planes, the ailerons and the other elements of the aeroplane are as usual in any of the well-known types.

My improvement pertains to means to be brought into use where the ailerons or their wires become broken or damaged to such an extent as not to be serviceable. I avoid the use of wires and employ rods of sufficient strength to withstand all possibility of derangement or disability from this source. For this purpose I employ two blades or wings 3 and 4, which are made strong and durable so as to withstand the strain and pressure to which they are likely to be subjected in flying.

Referring to Figures 4, 5, 6 and 7, 5 designates the shaft of the blade or wing, the

body 6 of which is formed preferably of aluminum, being of the flattened oval shape, seen in Figure 7, being rounded upon its upper and lower faces, as in Figure 7, the 5 sides coming to a point, as seen at 7, and the sides tapered to a point, as seen at 8, which may be more or less rounded. The portion of the shaft 5 within the body 6 is flattened, as seen at 9, and provided with 10 the alternately disposed pointed projections 10, as seen clearly in Figures 5 and 6. This flattened pointed portion of the shaft is molded or cast within the aluminum body 6 with the alternately oppositely disposed 15 portions 10 extended flatwise toward the opposite tapered edges 7 of the blade or wing, as seen best in Figures 5 and 6. This makes a blade that is light, yet strong and durable and one that is rigid and practically 20 homogeneous with its shaft.

As before stated, there are two of these blades or wings, one upon each side, near the front, as seen in Figure 2, the shaft 5 of each being mounted most substantially 25 in a bearing 11 supported in the arms 12 and 13, see Figures 5 and 2, and in a further bearing 14 rigidly secured to the plate 15 as by bolts, screws or the like 16, which plate 15, in turn, is designed to be firmly 30 secured to the engine bed, as by bolts, see Figure 1.

Suitable ball bearings 18 and 19 are provided for the shaft in these bearings, as seen in Figure 4, and suitable oil cups 20 35 are provided, as seen in Figures 4, 5 and 7. 18^a is a ball in the bearing 14 to take the end thrust of the shaft 5.

Rising from the shaft 5 between the bearings 11 and 14 is an arm 21, the outer end 40 of which is bifurcated, as seen at 22, or otherwise adapted to have connected therewith a rod 23, see Figures 1, 2 and 3. Each of these rods is provided with an upward bend 24 adjacent its connection with the arm 21, as seen in Figures 1 and 3, and the arm 13 is provided with a bend 25, as seen in Figures 2 and 5, so as to readily 45 permit of the requisite movement of the shaft and its rod, so as to allow the blade 50 or wing to be turned from a horizontal to a substantially vertical plane.

The position of the planes 3 and 4 is determined and controlled by means of two levers 26 and 27 mounted upon a pivot 28 55 and accessible to the pilot in the fuselage, as seen in Figure 1, the rods 23 extending convergently from their points of connection with the arms 21, as seen in Figures 2 and 3, and connected at their rear ends, 60 as at 29, with the lower ends of the levers 26 and 27, seen in Figure 3. The upper ends of these members straddle an arcuate member 30 fixedly secured in place and provided with a rack or toothed member 31 65 with which engage suitable pawls carried

and controlled by the handle portions 32 of the levers.

In use, my improved mechanism may be employed whether the ailerons or their control wires are broken or not, and if not 70 broken, will shorten the turn of the machine. If the aileron wires are broken, by pushing one of my control levers forward and the other backward it will cause the machine to make a turn to the left. If the control 75 levers are moved in the reverse direction the result will be a turn to the right.

In preventing a nose-dive, the two control levers are moved to the front; in this case my control blades take the place of the 80 broken flippers. To make a nose-dive the control levers are moved in the opposite direction.

In making a loop-the-loop, if my improved control device is used in connection 85 with the ordinary flippers one can make the loop-the-loop in almost the length of the machine.

In making a landing on a smooth field, 90 by placing the control levers straight only about the time the machine strikes the ground the speed of the plane will be materially reduced.

In making a forced landing, as upon a very bad field, by putting the control levers 95 half way from neutral to the front, the blades will lift the heavy weight of the motor and thus prevent the plane from striking the ground with much force, and saves the machine from tipping over on its nose. The controlling blades or wings 3 and 4 may be 100 actuated in unison, or independently of each other.

Modifications in detail may be resorted to 105 without departing from the spirit of the invention or sacrificing any of its advantages.

What is claimed as new is:—

1. In an aeroplane, a blade consisting of 110 an aluminum body of flattened form, and a shaft therefor having laterally extended portions molded within the aluminum body, the end of the shaft extended to and forming the point of the blade.

2. In an aeroplane, a blade consisting of 115 an aluminum body of flattened form, and a shaft therefor having laterally extended portions molded within the aluminum body, said body being of elongated oval cross-sectional form with its end extended to and forming the point of the blade.

3. In an aeroplane, a blade consisting of 120 an aluminum body of flattened form, and a shaft therefor having laterally extended portions molded within the aluminum body, said body being of elongated oval cross-sectional form and tapered both longitudinally and transversely, the end of the shaft extended to and forming the point of the blade.

4. In an aeroplane, a blade consisting of 125

- an aluminum body of flattened form, and a shaft therefor having laterally extended portions molded within the aluminum body, said shaft having a rigid lateral arm.
5. In an aeroplane, a blade consisting of an aluminum body of flattened form, a shaft therefor having laterally extended portions molded within the aluminum body, said shaft having a rigid lateral arm, and a bearing for said shaft provided with a ball to receive the end thrust of the shaft.
6. In an aeroplane, an air-foil control shaft bearing having arms with means for the attachment thereof to the engine bed, and means to take the end thrust of the shaft.
- 10 7. In an aeroplane, a shaft bearing having arms with means for the attachment thereof to the engine bed, and means to take the end thrust of the shaft, said bearing comprising arms extended from the base and one of which is provided with an inward bend.
- 15 8. In an aeroplane, a shaft bearing having arms with means for the attachment thereof to the engine bed, means to take the end thrust of the shaft, said bearing comprising arms extended from the base and one of which is provided with an inward bend, and a shaft having a lateral member for attachment to an arm for actuating the shaft to vary the inclination of its blade.
9. In an aeroplane, a shaft bearing having arms with means for the attachment thereof to the engine bed, means to take the end thrust of the shaft, said bearing comprising arms extended from the base and one of which is provided with an inward bend, a shaft having a lateral member for attachment to an arm for actuating the shaft to vary the inclination of its blade, and a rigid arm connected to said member.

In testimony whereof I affix my signature.

FRIEDERICK BAER.
